FIG_1

FIG_2

FIG_3

FIG_4

FIG_5

FIG_6

FIG. 7

FIG. 8

FIG. 1 is a perspective view of a gas ratio controller embodying our new design;

FIG. 2 is a front elevational view of the same;

FIG. 3 is a top plan view of the same;

FIG. 4 is a side elevational view of the same, the two side views being symmetric and therefore substantially identical;

FIG. 5 is a bottom plan view of the same;

FIG. 6 is a rear elevational view of the same;

FIG. 7 is a front perspective view of a modified form of gas ratio controller embodying our new design, the three major elements of the body being shaded to indicate that each element has a different color or shade; and

FIG. 8 is a rear perspective view of the same.

We claim:

The ornamental design for a gas ratio controller, substantially as shown and described.
